G. GODDU

FASTENING INSERTING MACHINE

Filed May 31, 1918

George Godden
By his Attorney
Nelson W. Howard

UNITED STATES PATENT OFFICE.

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed May 31, 1918. Serial No. 237,418.

To all whom it may concern:

Be it known that I, GEORGE GODDU, a citizen of the United States, residing at Winchester, in the county of Middlesex and 5 State of Massachusetts, have invented certain Improvements in Fastening-Inserting Machines, of which the following description, in connection with the accompanying drawings, is a specification, like reference 10 characters on the drawings indicating like parts in the several figures.

This invention relates to fastening inserting machines and particularly to fastening inserting machines employing previously formed fastenings.

In the type of machine shown in patent to Goddu, No. 490,624, granted January 24, 1893, fastenings are supplied to the fastening inserting mechanism by means of a 20 hopper mounted on a stationary part of the machine frame and a raceway carried by the oscillatory head, the upper end of the raceway being slideable in the hopper. When it becomes necessary or desirable to change the 25 kind of fastenings being driven, the hopper and the raceway must be emptied and other fastenings substituted. Various arrangements designed to facilitate emptying the hopper and raceway have been proposed in 30 machines of this general type but none is entirely satisfactory, especially in view of the time involved in effecting removal of the fastenings. Although it is seldom necessary to change the kind of fastenings in such 35 machines in ordinary shoe factory use so that the amount of time consumed in such an operation is not a matter of importance, in the use of such a machine as a shoe repair machine it very frequently becomes necessary 40 to change the kind of fastenings to suit the work offered for repair. Under such circumstances it is highly desirable to be able to obtain suitable fastenings at the point of fastening insertion, as the character of the work changes, with the minimum expenditure of effort and time.

The present invention is disclosed herein as embodied in a machine of the type disclosed in said Letters Patent No. 490,624, 45 though it should be noted that in various of its aspects it is not limited to use in connection with a machine of that type.

It is an object of the present invention to provide improved means for supplying fas-

tenings of various kinds selectively to the inserting mechanism in machines designed to handle loose fastenings in bulk and to feed them to fastening driving position along chutes or raceways. 55

In accordance with this object, a feature of the invention comprises a novel, easily attachable and detachable, magazine-and-raceway unit designed to supply headed fastenings, such as nails, in bulk. A number of these magazine-and-raceway units may be kept on hand, each filled with a different size or style of fastening. Each unit is provided with means arranged to co-operate with guiding and supporting means on the machine frame so as to support a selected 70 unit in proper delivery position with respect to the fastening inserting mechanism of the machine. Preferably gaging means are provided to limit the movement of the unitary structure as it is moved sidewise into position to determine its proper fastening delivery position. 75

Other features of the invention are found in the means which contribute to the ease and celerity with which a magazine-and-raceway unit may be attached to and detached from the machine, for example, in making selective use of the interchangeable magazine-and-raceway units. Preferably each magazine-and-raceway unit comprises movable means for arranging the fastenings properly in the raceway for delivery to fastening inserting position. Hence there is provided on the machine frame power-driven means arranged to effect, in a novel manner, operative connection with the movable means of the magazine-and-raceway unit to cause operation of the same. The construction for effecting the operative connection referred to is of such a character that no obstruction is offered to the movement of the magazine-and-raceway unit into its proper position on the machine frame. 90 95

In one aspect of the invention, important features consist in an organization by which suitable fastenings may be obtained readily at the point of fastening insertion simply by selecting the fastening-supplying unit containing the desired fastenings and almost instantaneously attaching said unit to the machine. 100 105

A further feature of importance relates

to the construction of the lower end of the raceway and of the nail throat. Ordinarily the throat and the raceway present projecting surfaces some or all of which have to be ground down repeatedly in securing the proper fitting together of these parts at the time the machine is assembled. Moreover, a fine degree of adjustment is usually required in positioning the raceway in proper fastening delivery relation to the nail throat. The raceway and throat disclosed herein are characterized by marked simplicity in construction and by the ease with which they may be assembled in proper fastening delivery position.

In order that the interchangeable fastening supplying units may be readily accessible at all times, a specially constructed bracket is mounted on the standard of the machine and is provided with means for receiving and holding each unit so that it may be readily removed and replaced on the bracket.

Other important features and objects of the invention will appear from the following description and claims when considered in connection with the accompanying drawings.

In the drawings,

Fig. 1 is a view in front elevation of a fastening inserting machine showing my invention applied thereto;

Fig. 2 is a detail view showing the devices by which the magazine-and-raceway unit is secured to the frame of the machine;

Fig. 3 is a detail view of a portion of the means for driving the rotatable magazine;

Fig. 4 is a view in section of a clamp member for holding the magazine-and-raceway unit in position;

Fig. 5 is an enlarged view of one of the brackets for supporting a magazine-and-raceway unit;

Figs. 6 and 7 are detail views of the lower end of the raceway and the fastening receiving and guiding throat.

Fig. 8 shows a magazine and raceway unit; and

Fig. 9 is a view in detail of the delivery end of the raceway with the fastening retaining finger withdrawn from the slot of the raceway.

For the purpose of illustration, the invention is shown as applied to a machine of the type disclosed in the patent to Goddu referred to above. The chief features of construction of this machine are found in the oscillatory or swinging head 6 which carries the driver bar 8 and the awl operating mechanism 10 for causing the awl 11 to penetrate the work and feed the same over the horn 12 in proper position for the insertion of the fastening by the driver 14. In order to supply fastenings to the throat 15 of the inserting mechanism, there is pro-

vided a magazine 16 and a raceway 18 which, in accordance with the present invention, are formed preferably as a unitary structure arranged to be detachably secured in position on the machine frame. As the fastenings reach the lower end of the raceway they are separated one by one and shoved into the throat or nail guiding passageway by means of a separator 20 operated from a lever 22 as clearly disclosed in Fig. 2 of the drawings.

In order to secure the magazine-and-raceway unit 24 in proper fastening delivering position on the machine frame there are provided on the unit and on the machine frame interengaging securing and positioning members comprising, in the preferred form, a forked member 26 designed to engage the headed member 28 as the magazine-and-raceway unit is moved bodily, side-

wise into position. After the members 26 and 28 are properly positioned relatively to each other the handle 30 is turned in one direction to cause the eccentric 32 to move the clamp member 28 downwardly, thus firmly clamping member 26 on the support 34, a spring 36 being provided to assist in releasing the clamp member 28 as the handle 30 is turned in the opposite direction. An additional securing means is provided preferably in the form of a rod 38 fixedly secured to the upper end of the magazine-and-raceway unit and designed to be clamped in the split collar 40 upon proper manipulation of the adjusting member 42.

The split collar 40 and the clamping member 28, 34 are carried upon a bracket 44 fixedly secured to the oscillatory head 6. Adjustably secured in this same bracket 44 are two positioning members 46 which are operative to engage the magazine-and-raceway unit at two widely separated points on the surface thereof to limit the movement of the unit inwardly toward the machine frame and thus, as gages, to determine the proper fastening delivery position of the unit.

In order to furnish support for the free end of the bracket 44, that is for the end unattached to the oscillatory head, there is conveniently provided an extension 48 on the main frame 50 of the machine, the said extension carrying loosely pivoted thereon a rod 52 arranged to telescope with a portion of the bracket 44 as clearly disclosed in Fig. 2 of the drawings.

Freely movable means of support for the outer end of the bracket is rendered necessary by the fact that the bracket is carried by the oscillatory head as already pointed out. It will be obvious that in placing the magazine-and-raceway unit in proper fastening delivery position in the machine it is necessary only to see that the forked member 26 is engaged with the clamp member 28 and that the member 38 enters the collar 40, the clamp member and

the extension 48.

It will be apparent that the magazine-and-raceway unit 24 may be moved laterally to any position desired on the machine frame and the forked member 26 will engage the headed member 28 as the unit is moved laterally.

It will be apparent that the magazine-and-raceway unit 24 may be moved laterally to any position desired on the machine frame and the forked member 26 will engage the headed member 28 as the unit is moved laterally.

collar acting not only as securing means but as guiding means while the unit is being moved sidewise into engagement with the positioning members 46 which limit the 5 movement of the unit and determine its proper position on the machine frame. When in proper position manipulation of the handle 30 and the hand wheel 42 operates to secure the magazine-and-raceway 10 unit fixedly in position.

While the raceway structure is being moved into proper fastening delivery position, a spring member 53, having a fastening retaining finger 55 extending across the 15 delivery end of the raceway, is moved by contact with the front face of the nail throat to cause the withdrawal of the finger 55 see Fig. 9 thus permitting the fastenings to come into contact with the fastening separator 20. While the magazine-and-raceway structure is being removed from the machine, the spring member 53 returns the finger 55 to a position to retain the fastenings in the raceway. In the present embodiment of the invention, the magazine-and-raceway units are designed to supply each a different size of fastening from those supplied by the other units. Inasmuch as fastenings may differ considerably in length 20 while varying but little in width or thickness of the shank, the same separator 20 without adjustment may be used to separate the fastenings supplied by the various magazine-and-raceway units designed, as in this 25 case, to supply fastenings of various lengths for repair work.

The raceway 18 is detachably secured to the magazine and raceway unit 24 by bolts 56 which pass through openings in the race- 40 way of greater size than the diameters of the bolts in order to permit the raceway to be adjusted relatively to the remainder of the unit 24. Vertical adjustment of the delivery end of the raceway 18 may be effected 45 if desired by any means suitable or usual for this purpose.

Preferably the magazine - and - raceway unit comprises a hopper 54, stationary with respect to the raceway, and a rotatable 50 magazine 16, the latter being operated by a shaft 58 carrying a disk 59 having a slot 60 cut through its periphery and extending relatively near to the center of the disk. Mounted upon the raceway is a raceway 55 clearer 62 arranged to be driven from a shaft 64 carrying an arm 66. When the magazine-and-raceway unit is shoved into position on the machine frame the disk 59 will engage the face of a co-operating driving member 68 carried at the end of a shaft 70 driven by mechanism hereinafter described. In order that there may be no obstruction to the movement of the magazine-and-raceway unit into contact with the positioning members 46 the pin 72 is yield-

ingly carried by the member 68 as clearly disclosed in Figs. 2 and 3 of the drawings wherein a spring 74 is shown in contact with the rear face of the pivoted block 76 which carries the pin 72. With the magazine and raceway in position, rotation of the shaft 70 and therefore of the member 68 will cause the pin 72 to move over the face of the disk 59 until it finally engages the slot 60, thus effecting an automatic connection between the driven shaft 70 and the shaft 58, and in this way providing for the rotation of the magazine 16. Mounted in the frame 50 is a short shaft 78 which is arranged to be driven from the same mechanism that causes rotation of the shaft 70. An arm 80 mounted upon the outer end of the shaft 78 carries a pin 82 so arranged as to contact with the arm 66 on the clearer shaft 64 to cause rotation of the clearer 62. Shafts 70 and 78 carry pulleys 84 and 86, respectively, connected by belts 88 and 90 to pulleys on the shaft which carries the large gear 92, the latter being driven from a small gear on the main shaft of the machine, as disclosed in said patent to Goddu. It will be apparent from the description that operative connections are established between the rotatable magazine and the raceway clearer and the driving means for the same at the moment that the magazine-and-raceway structure arrives in proper fastening delivering position of the machine frame, and that this is accomplished without any attention or effort on the part of the operative engaged in assembling the selected magazine-and-raceway structure with the fastening inserting machine. 95

A feature of importance which facilitates the adjustment of the raceway and contributes to the ease with which the magazine-and-raceway unit may be assembled with the machine is found in the construction of the lower end of the raceway and the nail throat where these two members come into contact with each other. As shown, in Figures 6 and 7 of the drawings, the lower end of the raceway consisting of projecting portions 94 and 96 presents a plane end surface adapted to slide smoothly over a plane surface on the nail throat 15, the latter being a continuation of the driver guide 98. Because of the construction described the end of the raceway may be moved or adjusted in any direction while in contact with the plane surface 100 of the nail throat 15. Thus, it is possible to adjust the lower end of the raceway vertically with respect to the separator 20 so as to bring the separator as near as possible to the head of the fastening. Moreover, the lower end of the raceway may be readily adjusted so as to bring the slot 102 of the raceway into proper alinement with the passage or slot 104 in the surface 100 leading into the nail passage in the nail 100

throat. As heretofore constructed, the lower end of the raceway and the nail throat had projecting portions which had to be carefully fitted together, thus making adjustment in both vertical and lateral directions difficult to carry out and, if the adjustment between the raceway and throat were not properly made, the fastenings in the raceway would fail to be delivered properly to the nail throat with the result that fastenings might be jammed in the passageways, thus reducing materially the output of the machine. In the construction herein shown a further feature of importance disclosed in Fig. 7 consists of the provision of a wide slot through the surface 100 of the nail throat which slot leads into the nail passage at the throat and is practically as wide as the diameter of the circular passageway. Inasmuch as the slot 102 in the raceway is considerably narrower than the slot 104 it is correspondingly easy to make the proper adjustment of the raceway since the median line in slot 102 does not have to coincide with the median line in slot 104 but can be displaced to one side or the other thereof to a substantial amount and still deliver the fastenings properly into the nail passage of the nail throat. Conveniently, the nail head supporting surfaces of the raceway are beveled off at their lower ends as disclosed in Fig. 7 to permit the fastening to drop slightly as it reaches the lower end of the raceway, thus bringing the nail head nearer to the upper edge of the separator, this arrangement having the advantage that the fastenings, and particularly the shorter fastenings, are moved more surely into the nail throat and kept in proper alignment with the throat while being so moved.

As clearly indicated in Fig. 1 of the drawings, a plurality of fastening supplying units is provided for use with the machine constructed according to this invention, to enable the substitution of fastenings of one kind for fastenings of another kind whenever it may become desirable or necessary by reason of changes in the nature of the work being operated upon. It will be obvious that fastenings of various kinds, or more specifically of various sizes, may be delivered to fastening driving position by selectively using the interchangeable fastening supplying units provided with the machine and shown supported in a location readily accessible to the operative so that a change in fastenings may be made with the minimum expenditure of time and energy. The support for the magazine-and-raceway units is shown in Fig. 1 to consist of a bracket 106 conveniently secured to the standard 108 of the machine, the said bracket carrying a plurality of auxiliary brackets 110 each designed to support a single magazine-and-raceway structure 24. Each auxil-

iary bracket 110 comprises a concave seat 112 adapted to receive the convexly curved surface of a magazine 16. Each said bracket comprises further an abutment 114 notched as shown at 116 for the reception of the lower or rear edge of the raceway. Thus, when a magazine-and-raceway unit is placed upon its individual bracket with the convexly curved surface of the magazine resting in the seat 112, the said unit turns rotatably in the seat 112 until the lower or rear edge of the raceway contacts with the notched end of the abutment 114, the said abutment thus serving to limit movement of the unitary structure in the seat 112 and also to hold the structure against displacement laterally in the bracket.

It is thought that the manner of using and operating the various elements in which are embodied the important features of the invention will be obvious from the detailed description of the construction as given above and that no further description thereof is necessary.

Having described my invention, what I claim as new and desire to secure by Letters Patent of the United States is:

1. In a nailing machine, means on the machine frame for supporting in proper delivery position one of a plurality of interchangeable nail-supplying units, each of said units comprising a rotatable magazine, a raceway clearer, means to operate the clearer and magazine, and a raceway for delivering nails to nailing position, and power driven means on the machine frame operative to engage the means which operate the clearer and magazine of any one of the interchangeable units as the selected unit is moved to its proper position on the machine frame.

2. In a nailing machine, means on the machine frame for supporting in proper nail delivery position thereon one of a plurality of interchangeable magazine and raceway units designed to supply nails of various sizes and arranged to be readily attached to and detached from the machine, each of said units comprising a hopper, a rotatable magazine and movable means for arranging nails for delivery to nail driving position, and power-driven means on the machine frame operative to engage with said movable means, in any one of the interchangeable magazine-and-raceway units, as the selected unit is moved sidewise to its proper position on the machine frame to cause operation of said movable means.

3. In a fastening inserting machine designed to receive fastenings of various sizes in bulk and to feed the same to driving position and to drive said fastenings, means on the machine frame for holding and positioning thereon one of a plurality of interchangeable magazine-and-raceway units de-

- signed to supply fastenings of various kinds, each of said magazine-and-raceway units being provided with engaging means to co-operate with the holding and positioning 5 means on the frame, and means for retaining the fastening in the raceways of said units when they are not in use constructed and arranged to release the fastenings as a selected unit is moved into fastening 10 livery position.
4. In a fastening inserting machine designed to receive fastenings of various sizes in bulk and to feed the same to driving position and to drive said fastenings, means on 15 the machine frame for holding and positioning thereon one of the plurality of entirely separate and interchangeable magazine-and-raceway units designed to supply fastenings of various kinds, each of said magazine-and-raceway units being provided with a plurality of receiving and positioning 20 members constructed and arranged to enter into co-operative engagement with the holding and positioning means on the frame during bodily movement of the selected magazine-and-raceway unit as said unit is moved bodily sidewise in applying it to the frame, the construction and arrangement being such 25 that fastenings of various sizes may be delivered to fastening driving position by 30 selectively using the interchangeable magazine-and-raceway units.
5. In a fastening inserting machine, a magazine-and-raceway unit provided with 35 movable means for arranging fastenings for delivery to fastening inserting position, means on the machine frame for detachably supporting a single magazine-and-raceway unit and for guiding it into proper fastening 40 delivery position, and power-driven means on the machine frame constructed and arranged to effect operative connection with said movable means as the unit is moved sidewise into proper position on the 45 supporting means.
6. In a fastening inserting machine, a magazine-and-raceway structure provided with movable means for transferring fastenings from the magazine to the raceway, means 50 on the machine frame for detachably supporting the magazine-and-raceway structure in proper fastening delivery position, and power-driven means on the machine frame constructed and arranged to effect an operative 55 connection with said movable means as the structure is moved sidewise into proper position on the supporting means, said connection comprising a slotted disk and an eccentric pin yieldingly mounted so that it 60 may be displaced and thus offer no obstruction to the introduction of the structure into proper position and operative to engage the slot in the disk when the power-driven means is thrown into operation.
- 65 7. In a fastening inserting machine a head, fastening inserting mechanism carried by said head, a magazine-and-raceway unit detachably mounted on said head, and means located on the unit and on the head for guiding the unit into proper fastening delivery 70 position with respect to the inserting mechanism on the head and for securing said unit fixedly in such position, said means comprising a forked member in co-operation with a headed clamp member arranged to engage as the unit is moved sidewise into proper position and operative to hold the unit fixedly in proper position.
8. In a machine for inserting fastenings, a quickly attachable and detachable magazine-and-raceway unit, means on the frame of the machine for positioning and supporting said unit, and means for gaging the proper fastening delivery position of the unit by engagement therewith as it is moved 75 sidewise into said position.
9. In a machine having a magazine-and-raceway structure comprising a magazine having a convexly curved surface of substantial extent and a raceway having a narrow portion, a bracket to support said structure, said bracket being provided with a shallow concaved surface to receive the convexly curved surface of the magazine for rotation therein and with a notched abutment to receive the narrow portion of the raceway to limit the rotative movement of the magazine-and-raceway structure and to prevent lateral displacement of the structure on the bracket.
10. In a nailing machine, a stationary frame, a swinging head carried by said frame and provided with a bracket having thereon positioning and supporting means for a magazine-and-raceway unit, a magazine-and-raceway unit having engaging 100 means to co-operate with the positioning and supporting means on the bracket and provided with movable means for transferring nails from the magazine to the raceway, and means mounted on said stationary frame constructed and arranged to operate said movable means.
11. In a fastening inserting machine, a stationary frame, a swinging head carried by said frame and provided with fastening inserting mechanism, a magazine-and-raceway structure comprising movable means for arranging fastenings for delivery to the inserting mechanism, means 105 mounted on the swinging head for supporting the magazine-and-raceway structure in proper fastening delivery position, and means mounted on said stationary frame constructed and arranged to operate said movable means.
12. In a fastening inserting machine, the combination of a throat provided with a surface having a slot leading to the nail 110 passage in the throat, with a raceway and 120
- 125 130

magazine unit having the end surface of the raceway arranged to contact with said surface of the throat, and means for positioning the raceway and magazine unit laterally, the slot through the surface of the throat being wider than the slot in the raceway, whereby adjustment of the raceway laterally into proper fastening delivery position is readily attained.

10 13. In a fastening inserting machine, a throat provided with a plane surface having a slot leading to the nail passage in the throat, in combination with a raceway having a plane end surface arranged to contact 15 with said surface of the throat and a fastening separator, the plane surfaces of the raceway and throat permitting vertical adjustment of the raceway relatively to the separator, the slot in the surface of the 20 throat being wider than the slot in the raceway, whereby adjustment of the raceway laterally into proper fastening delivery position is readily attained.

14. In a fastening inserting machine, in 25 combination, an awl movable to penetrate the work and to feed it laterally, a throat, a driver movable through said throat, a head carrying said awl, driver and throat, means for moving the throat and awl alternately into and out of the line of drive 30 whereby the opening made by the awl is moved into the line of drive and the throat then returned to the line of drive, and a magazine-and-raceway unit mounted on 35 said head to supply fastenings in succession to said driver.

15. In a fastening inserting machine, in 40 combination, a stationary frame, an awl movable to penetrate the work and to feed it laterally, a throat, a driver movable through said throat, a head carrying said awl, driver and throat, means for moving the throat and awl alternately into and out of the line of drive whereby the opening 45 made by the awl is moved into the line of drive and the throat then returned to the line of drive, a magazine-and-raceway unit mounted on said head and provided with movable means for arranging fastenings for 50 delivery to fastening inserting position, a separator for controlling the delivery of fastenings in succession to the driver, and means mounted on said stationary frame constructed and arranged to operate said 55 movable means.

16. In a nailing machine, in combination, 60 a reciprocating head, nail inserting mechanism carried by the head, work feeding means carried by the head and arranged to feed the work to and past the nail inserting mechanism as the head reciprocates, and a magazine and raceway structure mounted on the head constructed and arranged to supply nails to the inserting mechanism.

65 17. In a fastening inserting machine, in

combination, a stationary frame, a reciprocating head carried thereby, fastening inserting mechanism carried by said head comprising an awl and a throat having a nail passage, said awl and nail passage being 70 moved alternately into the line of drive of the fastenings by reciprocation of the head so that the opening made by the awl is moved into the line of drive and the nail passage of the throat then returned to the 75 line of drive, and a magazine and raceway structure mounted on the head for movement therewith.

18. In a fastening inserting machine, a 80 magazine-and-raceway unit provided with movable means for transferring fastenings from the magazine to the raceway and arranged for ready bodily movement to and from the machine, means on the machine frame for detachably supporting the magazine-and-raceway unit and for ensuring its location at proper fastening delivery position when it is returned to the machine, and power-driven means on the machine frame constructed and arranged automatically to effect 85 an operative connection with said movable means during the attachment of the magazine-and-raceway unit as that unit is moved sidewise into proper position on the supporting means.

19. In a machine of the class described, a 90 frame, fastening inserting means on the frame, means for detachably supporting one of a plurality of interchangeable fastening supply units on the frame in position to 100 deliver fastenings to the fastening inserting means, and independent means carried by the frame for supporting other of said fastening supplying units.

20. In a machine of the class described, a 105 frame, fastening inserting mechanism, means for detachably supporting one of a plurality of magazine and raceway units in position to deliver fastenings to the inserting mechanism, and separate means on said frame for 110 supporting other of said magazine and raceway units in position to enable fastenings to be supplied readily to the magazines.

21. In a nailing machine, a frame, a member 115 movably mounted on the frame, means for moving said member, means carried by said member for detachably supporting one of a plurality of interchangeable nail-supplying units designed to supply nails of various sizes, and means on said frame for 120 operating a nail-supplying unit when in position on said member, said means being constructed and arranged to retain operative engagement with the nail-supplying unit during movement of said member.

22. In a nailing machine, a frame, a member 125 movably mounted on the frame, means carried by said member for detachably supporting one of a plurality of interchangeable nail-supplying units designed to supply 130

nails of various sizes, and means on said frame for operating a nail-supplying unit when in position on said member.

23. In a nailing machine, a frame, a head mounted for swinging movement on the frame, fastening inserting instrumentalities carried by the head, means on said head for detachably supporting one of a plurality of interchangeable nail-supplying units designed to supply nails of various sizes, and means on said frame for operating a nail supplying unit when in position on said member.

24. In a fastening inserting machine, a magazine-and-raceway unit, means for detachably supporting said unit on the machine, means at the outlet of the raceway of said unit for retaining fastenings in the raceway, and means for rendering the retaining means inoperative when the raceway is applied to the machine.

25. In a fastening inserting machine, a driver, a driver guide, a raceway, means for detachably supporting the raceway on the machine, and means for retaining fastenings in the raceway constructed to be rendered inoperative by the driver guide when the raceway is applied to the machine.

26. A fastening supply device for fastening inserting machines comprising a unitary magazine and raceway arranged to be readily applied to and removed from a fastening inserting machine, and having a fastening retainer at the outlet of the raceway arranged to become inoperative as the device is applied to a fastening inserting machine and to become operative to retain fastenings in the raceway as the device is removed from the machine.

27. A fastening supplying device for fastening inserting machines comprising a unitary magazine and raceway arranged to be readily applied to and removed from a fastening inserting machine, and having a fastening retainer at the outlet of the raceway provided with a finger positioned for engagement with a portion of the machine as the supply device is applied thereto to render the retainer inoperative as long as the supply device remains upon the machine.

28. A fastening supply device for fastening inserting machines comprising a unitary magazine and raceway arranged to be readily applied to and removed from a fastening inserting machine, and having a fastening retainer at the outlet of the race-

way comprising a resilient member provided with a fastening retaining portion and a finger arranged for engagement with a portion of the machine to render the retainer inoperative as the supply device is applied to the machine.

29. A fastening supply device for fastening inserting machines comprising a magazine unit raceway and connecting members carried thereby and arranged for ready cooperation with complemental connecting members carried by a machine to which the unit is to be applied to permit the unit to be speedily removed from the machine or applied to the machine in definite relation to the throat of the machine, and a finger carried by the raceway and arranged to prevent the escape of fastenings when the unit is removed from the machine.

30. A fastening supply device for machines for inserting fastenings comprising a unitary magazine and raceway provided with a power operated part and a driving member for said part carried by the fastening supplying device and arranged, as the device is applied to a fastening inserting machine, for automatic engagement with a complemental power-driven member carried by the machine to operate the supply device.

31. A fastening supply device for fastening inserting machines comprising a unitary magazine and raceway provided with power-operated parts and separate driving members for said parts carried by the fastening supply device and arranged as the device is applied to a fastening inserting machine for engagement severally with complemental power driven members carried by the machine.

32. A fastening supply device for fastening inserting machines comprising a bodily removable unitary magazine-and-raceway, means carried by the supply device for cooperation with portions of a machine to which the device may be applied for guiding the supply device into fastening delivery position with respect to the throat of the machine as the unitary magazine-and-raceway is applied to the machine, and positioning means arranged absolutely to prevent movement of the supply device past fastening delivery position as it is attached to the machine.

In testimony whereof I have signed my name to this specification.

GEORGE GODDU.

Certificate of Correction.

It is hereby certified that in Letters Patent No. 1,514,613, granted November 11, 1924, upon the application of George Goddu, of Winchester, Massachusetts, for an improvement in "Fastening-Inserting Machines," an error appears in the printed specification requiring correction as follows: Page 7, line 65, claim 29, for the words "unit raceway and" read *and raceway unit*; and that the said Letters Patent should be read with this correction therein that the same may conform to the record of the case in the Patent Office.

Signed and sealed this 17th day of February, A. D. 1925.

[SEAL.]

KARL FENNING,
Acting Commissioner of Patents.
